UNITED STATES PATENT OFFICE

JOHN SAMUEL IRVING AND EDWARD ARTHUR GREEN, OF COVENTRY, ENGLAND, AS
SIGNORS TO THE HILLMAN MOTOR CAR COMPANY LIMITED, OF COVENTRY, ENGLAND

DESIGN FOR AN AUTOMOBILE RADIATOR COVER

Application filed February 20, 1930, Serial No. 34,600, and in Great Britain January 14, 1930.
Term of patent 3½ years.

To all whom it may concern:

Be it known that we, JOHN SAMUEL IRVING and EDWARD ARTHUR GREEN, subjects of the King of England, and residents of Hillman Works, Pinley, Coventry, Warwickshire, England, have invented a new, original, and ornamental Design for an Automobile Radiator Cover, of which the following is a specification, reference being had to the accompanying drawing, forming part thereof, in which—

Figure 1 is a front perspective view and Figure 2 is a side view of a radiator cover illustrating our new design.

We claim:

The ornamental design for an automobile radiator cover as shown.

JOHN SAMUEL IRVING.
EDWARD ARTHUR GREEN.
